UNITED STATES PATENT OFFICE.

DAVID CLARK WEAVER, OF SALEM, OREGON, ASSIGNOR OF ONE-HALF TO SUSAN J. WEAVER, OF SALEM, OREGON.

GUARD.

1,235,403.

Specification of Letters Patent. Patented July 31, 1917.

Application filed October 20, 1916. Serial No. 126,741.

To all whom it may concern:

Be it known that I, DAVID C. WEAVER, a citizen of the United States, residing at Salem, in the county of Marion and State of Oregon, have invented new and useful Improvements in Guards, of which the following is a specification.

The invention relates to an improved guard designed for use in wood working machines, particularly with planers of the 10 type known as jointer or bur planers.

The improved guard is designed to cover and protect the knives at all times, except when in actual use, whereby it is impossible 15 for the workman to become injured by the knives.

The invention in the preferred form of details will be described in the following specification, reference being had particularly to 20 the accompanying drawings, in which:—

Figure 1 is a plan view showing the planing machine with the improved guard applied thereto.

Fig. 2 is a side elevation of the same. 25 Fig. 3 is a side elevation from the opposite side.

Fig. 4 is a perspective view of the guard proper and connection.

Fig. 5 is a plan view of the guard ex- 30 tended.

Fig. 6 is a transverse section through the guard.

Referring particularly to the accompanying drawings, the improved guard comprises 35 a metallic member 1, the side edges of which are divergent from the supported end of said member to provide a comparatively wide operative end 2. The under side of the member 1 is recessed at 3, said recess open- 40 ing through the outer side of the member and through the inner end providing an abutting wall 4 at the inner side of the member, as shown. An adjusting plate 5 is movably fitted in the recess 3, and adjust- 45 able laterally with relation to the main member 1, being formed with a series of open- 50 ings 6 adapted to coöperate with the pin 7 depending from the main member, whereby the plate may be held at variable lateral ad- 55 justments with respect to the main member, for a purpose which will later appear.

The guard including a main member 1 and an adjusting plate 5 is rotatably supported upon a shaft 8 having a reduced 55 upper end 9 to seat in registering openings

10 in the adjusting plate and main member, the opening in the plate being formed with lateral recesses 11 to receive the cross pin 12 mounted in the shaft, whereby the shaft and plate are fixed against independent 60 movement. A set screw 13 passes through an opening in the top of the main member and is threaded into the end of the shaft to secure the parts against endwise separation. 65

The shaft 8 is rotatably mounted in the opening 14 formed in the top 15 of the planer in advance of the planing knives 16, so that the operative end of the guard over- 70 lies and protects said knives being held against fixed guide 17 through the medium of an operating means, including a rod 18 removably inserted in the opening 19 formed transverse the shaft and extending trans- 75 verse the planer top beneath the same. The rod is headed so that it may be freely re- moved from the shaft in one direction, the opposite end of the rod being formed with a notch 20 to receive one end of the cable 21, the opposite end of which is connected 80 to the weight 22 passing over the guide pul- 85 ley 23 secured to the planer. The weight operates to exert a sufficient pull upon the rod 18 to maintain the guard overlying the knives and against the fixed guide. 85

In operation, the guard will effectively protect the knives, maintaining them cov- 90 ered except during actual use, it being under- 95 stood that the material to be operated upon is introduced alongside the edge of the guard and displaces the same as it is ad- 95 vanced to be engaged by the knives. When the guide 17 has been adjusted to give a wider cut the guard may be correspondingly increased in size by adjusting the plate 5 with relation to the main member as hereto- 100 fore described.

For convenience, in dismantling the guard, I provide hook 25 adjacent the weight connection, so that the latter may be 100 suspended, the cable end removed from the rod 18, the latter removed from the shaft opening and the guard and shaft together removed from the planer top.

What is claimed is:—

1. A guard for planer knives operating through a planer table, comprising a vertical shaft rotatably mounted in the table re- 110 mote from the knives, means for maintain- ing rotative tension on the shaft in one

2
direction, a guard for the knives including a main plate arranged to coöperate with the shaft, with interlocking means on the plate and shaft to hold the plate against independent rotary movement on the shaft while permitting free longitudinal movement of the plate in one direction, a second plate mounted for rotative movement on the shaft, the ends of the plates remote from the shaft and adjacent the knives being arranged for relative adjustment and locking of the plates.

2. A guard for planing knives operating through a table comprising a shaft mounted for rotative movement in the table remote from the knives, an arm extending from the shaft, a weight connected to the arm to maintain rotative tension on the shaft, and

a guard comprising a main plate having a bearing to engage the shaft, said bearing being formed with a slot to engage a pin carried by the shaft to fix the main plate on the shaft, a second plate superimposed on the main plate and mounted on the shaft for free rotative movement, the main plate remote from the shaft being formed with a series of apertures, and a pin carried by the second plate to engage in any one of the apertures in the main plate to adjust the plates with respect to each other.

In testimony whereof I affix my signature in presence of two witnesses.

DAVID CLARK WEAVER.
